Att. -

UNITED STATES PATENT OFFICE.

WILLIAM HASTINGS HUTTER, OF EVANSTON, ILLINOIS.

SELF-RESISTER EXERCISING DEVICE.

1,372,026.

Specification of Letters Patent. Patented Mar. 22, 1921.

Application filed July 28, 1919. Serial No. 313,840.

To all whom it may concern:

Be it known that I, WILLIAM H. HUTTER, a citizen of the United States, residing at Evanston, in the county of Cook and State 5 of Illinois, have invented certain new and useful Improvements in Self-Resister Exercising Devices, of which the following is the specification.

This invention relates to exercising apparatus of the type wherein a rope is pulled back and forth over a pulley to exercise the muscles of the arms, legs, neck, back, and other portions of the body, the following, among others, being objects of the invention: to enable the user to keep a substantially constant tension of any desired amount within his capacity on the ropes during use; to enable the user to vary the tension according to his desires and ability 10 without any adjustment of parts; to provide mechanism whereby the user can readily determine how much tension he is placing on the flexible member; to provide means for readily interchanging certain elements on which the user exerts a pull in use, to enable him to utilize the device for exercising different portions of his anatomy; to provide improved means for adjusting the length of the flexible tension cord; 15 to enable the user to make one portion of his body serve as a resistance against which another portion thereof acts.

The above and other features inherent in this invention will become apparent from the 20 detailed description following, when taken in connection with the annexed drawings, which description and drawings are intended as illustrative only and not as limiting applicant's invention.

40 In the drawings:

Figure 1 is a perspective view of my device in operative position.

Fig. 2 is a perspective view of a head, neck, or body engaging loop.

45 Fig. 3 is an enlarged perspective view of the rope adjusting means.

Fig. 4 is a perspective view partly in section and partly broken away.

50 Fig. 5 is a detail section of the platform and parts connected therewith.

Fig. 6 is a plan view of the lever used in my device, together with parts connected thereto.

55 Referring to the drawings in detail, the device comprises a platform P, force apply-

ing means F, tension transmitting and indicating mechanism T, and a head, neck, or body engaging element or loop H.

The platform P comprises upper and lower plate members 1 and 2 of rectangular 60 or other form, connected at their edges by side strips 3 and end strips 4 and 5, or they may be connected by a single strip or a plurality of strips, suitably joined, if the platform is made circular or of similar 65 form. The upper surface of the platform is shown provided with a sheet of rubber or other suitable means 6 for preventing the person from slipping when standing on the platform. The platform has an opening 7 70 through one face thereof, as the top or one edge member, which may be surrounded by a perforated finishing and wear-resisting member 8, secured to the platform structure by any suitable means such as screws. 75 In the device as I have illustrated it, I preferably use rubber for plate 6, metal for protecting ring 8 and wood for the remainder of the structure thus far described, but other materials may be used if desired. 80

The force applying means comprises a flexible element such as a rope, wire, chain, or other analogous connecting means 9 and a pair of handles 10 and 11, the former of which handles is connected adjustably and 85 the latter removably to the flexible element. The structure of these handles and their connection to the flexible element are obvious from the drawing, said handles comprising wire frames carrying wooden or 90 analogous grips, the handle 11 having a single eye for attachment of rope 9, and the handle 10 having two such eyes 12 and 13. The rope 9 passes from the fastening means connected to handle 11 through a friction 95 reducing means such as pulley 14, to and through eye 12, over a bar 15 slidably mounted on the frame of the handle 10, then under this bar and through eye 13. The purpose of this structure is to provide 100 easy adjustment for the length of the rope and means for securely holding the same in adjusted position.

The element H, which is adapted to be substituted for handle 11, is preferably constructed of woven goods, such as khaki, reinforced with leather at the narrow part 16 and wide part 17, and suitably edged with binding as shown; however, other suitable material may be used if desired. Ring 110

18 is held in place on the narrow part by suitable stitching. This element, which I will call the neck loop, may be substituted for handle 11 by disconnecting the latter 5 from the attaching means on the end of rope 9 and attaching ring 18 thereto. This ring may be of metal as shown, or of any other suitable material, and may be circular, flattened at one side, or of other desired 10 form.

The tension transmitting means comprises a suitable elastic member shown as a coil spring 19 connected at one end to an inner face of the platform, and at its other end 15 to one end of the lever 20. The other end of the latter is shown connected to a flexible member 21, which may be a chain, rope, or other suitable device. Member 21 passes over the pulley 22 supported on brackets 23 20 (suitably attached to the platform by screws or the like) and through opening 7, being attached at its end to friction reducing device 14, which is shown as a swivel pulley. A bracket 24 carries a suitable pivot point for 25 the fulcrum of lever 20 and is attached in any convenient manner, as by screws, to an inner face of the platform. Lever 20 is preferably a lever of the first class, as shown, but it might be either second or third class 30 if desired. Chain 21 is shown connected to lever 20 by a yoke member and a screw threaded member having an eye in one end and its threaded end screwed into the yoke member and held in adjusted position there- 35 in by a lock nut. It is of course understood that spring 19 is not a necessary element and may be dispensed with if desired.

Attached to a point on lever 20, preferably 40 the point of greatest motion when the device is in operation, is a flexible member such as wire 25, which passes into and through a flexible tube 26. This latter may be an ordinary flexible metallic tube, such as used 45 for gas tubing, and serves to keep undesirable bends and kinks from forming in wire 25. One end of this tube is held in place within the platform P by means of the metal cleat 27 or other suitable device.

The above described tube and wire are 50 connected at their remaining ends to the tension indicating device 28, which comprises a sort of box 29, an indicator 30 and a spring or other resilient device 31 connected as shown or in other appropriate 55 manner. Indicator 30 has an index 30' thereon coöperating with the scale on box 29. As shown, the wire 25 is connected to indicator 30, and spring 31 has its ends connected respectively to the indicator and a screw eye 32, which also assists in keeping 60 a hinged back 33 of the box closed and serves as a point of attachment for the suspending hook or loop 34, which in conjunction with eye 32 prevents back 33 from 65 opening.

The scale may be calibrated by connecting handle 10 or 11 to a fixed support, and applying to the other of these handles a known force, which will cause extension of spring 19 and will cause the index 30' to move down 70 along the face of box 29. An appropriate mark may then be placed on the face of this box to indicate the amount of tension used. Another force of greater or lesser value may then be applied to the handle, 75 which will cause a different amount of motion of the index, and a corresponding scale line will be placed upon the face of the box. This should be carried on until the desired number of scale marks are placed upon the 80 face of the box.

In operation the user will stand upon the platform and having adjusted the length of rope 9 to his needs for the particular exercise which he wishes to take, he will exert 85 a pull upon both handles until the index moves over the scale to such point as indicates the amount of force which he wishes to use. He will thereupon move one hand, if he is using his hands, toward the platform 90 and move the other hand away from said platform, at the same time maintaining the index upon the scale at a constant point, as nearly as may be convenient. In this manner, he will balance the force exerted by one 95 portion of the body against that exerted by another portion thereof and each will serve as a resistance to the other.

If the user desires to exercise more especially the muscles of the neck or a portion 100 of the back, he may remove handle 11 and substitute therefor the head loop H, placing this over the head, neck, or back, and carrying out any exercise considered desirable. I desire in this connection to emphasize the 105 fact that this device enables the user to act as his own resister while at the same time enabling him to exert a known and variable force against a resilient resistance.

I have suggested several variations of 110 form, materials, or structure merely as illustrations of some, but not all of the ways in which departure may be made from the preferred form without departing from the spirit of the invention.

Having now described my invention, I claim:

1. An exercising device of the class described, comprising a platform, variable-tension transmitting and indicating means 120 connected therewith including a resilient member within the platform, and force applying means connected with a part of the tension transmitting means whereby force exerted by a user of the device may be impressed upon the tension transmitting means and thereby transmitted to the indicator there being means independent of the tension transmitting means for operating the indicator.

2. An exercising device of the class described, comprising a platform, variable-tension transmitting and indicating means connected therewith, and force applying means connected with a part of the tension transmitting means whereby force exerted by a user of the device may be impressed upon the tension transmitting means and thereby transmitted to the indicator, the said 5 variable-tension indicating means comprising an index carrying member, a supporting member along which the index carrying member is longitudinally movable in accordance with the amount of 10 force exerted on the force applying means, and also comprising means for returning the said index carrying member to its initial position, means to connect the said member to the tension transmitting means, and 15 means for returning the tension transmitting 20 means to normal position.
3. An exercising device of the class described, comprising a platform, variable-tension transmitting and indicating means 25 connected therewith, a resilient member adapted to be put under stress by applied force, and force applying means connected with a part of the tension transmitting means whereby force exerted by a user of the 30 device may be impressed upon the tension transmitting means and thereby transmitted to the indicator, the said tension transmitting means comprising a flexible element connected at one end to the force applying 35 means, connecting means between the flexible and resilient members, and a connection therefrom to the indicator.
4. An exercising device of the class described, comprising a platform, variable- 40 tension transmitting and indicating means connected therewith, a resilient element having one end connected to the platform, and force applying means connected with a part of the tension transmitting means whereby 45 force exerted by a user of the device may be impressed upon the tension transmitting means and thereby transmitted to the indicator, the said tension transmitting means comprising a lever having a pivot connect- 50 ed to the platform, a second point of the said lever being connected to the said resilient element and a third point of the lever being connected by a flexible member with the force applying means, there being a connect- 55 ing element between the indicator and the lever.
5. An exercising device of the class described, comprising a platform, variable-tension transmitting and indicating means 60 connected therewith, and force applying means connected with a part of the tension transmitting means whereby force exerted by a user of the device may be impressed upon the tension transmitting means and thereby transmitted to the indicator, the 65
- said force applying means comprising a flexible element and a pair of handles connected thereto, one of said handles being adjustable along the length of the flexible element, the said tension transmitting means comprising a flexible element connected at one end to the force applying means, a resilient member adapted to be put under stress by applied force, connecting means between the flexible and resilient members, 70 and connection therefrom to the indicator, whereby in use the user may apply physical force to a somewhat yielding resistance and keep the same substantially constant while balancing the force of one part of the 75 body against that of another.
6. An exercising device of the class described comprising a platform, variable-tension transmitting and indicating means connected therewith, a force applying means 80 connected with a part of the tension transmitting means whereby force exerted by a user of the device may be impressed upon the tension transmitting means and thereby transmitted to the indicator, the said force 85 applying means comprising a flexible element, and a pair of handles connected thereto, one of the handles being replaceable by a head loop whereby the force exerted by the muscles of the neck and back may resist 90 95 and act against the force exerted by one or both of the arms.
7. A unitary exercising device of the class described, comprising a platform, variable-tension transmitting and indicating 100 means connected therewith, and force applying means connected with a part of the tension transmitting means whereby force exerted by a user of the device may be impressed upon the tension transmitting means 105 and thereby transmitted to the indicator, the said force applying means comprising a handle, a head loop and a flexible member connecting these elements to the tension transmitting means. 110
8. A handle for self-resister exercising machine having a flexible force applying member adapted to be drawn over a friction reducing means by bodily force of the user, comprising a frame, a grip, and a cross bar 115 adjustably mounted on the side bars of the frame, said frame having a bar connecting the side bars, said last named bar having eyes through which the flexible member may be threaded to provide for adjusting the 20 length thereof. 120
9. A variable tension mechanism for a self-resister exercising machine having a platform and mechanism for balancing a force exerted by one part of the body against 125 that produced by another part, comprising a lever having its pivotal point connected to the platform, a resilient means connected to another point on the lever and having another point fixed to the platform, and flexi- 130

ble means connected at one end to a third point on the lever having its other end portion connected to a force applying means, said platform being provided with friction reducing means over which the flexible means passes for connection to the force applying means.

In witness whereof, I hereunto subscribe my name to this specification in the presence of two witnesses.
